UNITED STATES PATENT OFFICE.

ANDREW TUCKER, OF FAIRFIELD, CONNECTICUT.

DESIGN FOR A WALL-BRACKET LIGHTING FIXTURE.

Application filed September 20, 1927. Serial No. 23,470. Term of patent 3½ years.

To all whom it may concern:

Be it known that I, ANDREW TUCKER, a citizen of the United States, residing at Fairfield, county of Fairfield, State of Connecticut, have invented a new, original, and ornamental Design for a Wall-Bracket Lighting Fixture, of which the following is a specification, reference being had to the accompanying drawing, forming part thereof.

Fig. 1 is a front elevation partially in section of a wall bracket lighting fixture showing my new design, the supporting arm and candle cup being omitted, and

Fig. 2 is a side elevation of the fixture.

I claim:

The ornamental design for a wall bracket lighting fixture, substantially as shown.

ANDREW TUCKER.
